* cited by examiner

Primary Examiner — Eric Goodman(74) *Attorney, Agent, or Firm* — Cooper & Dunham, LLP(57) **CLAIM**

The ornamental design for a hose connector, as shown and described.

DESCRIPTION

FIG. 1 is a right side view thereof;
 FIG. 2 is a front side view thereof; and,
 FIG. 3 is a left side view thereof.

The broken lines are included for the purpose of illustrating portions of the hose connector that form no part of the claimed design.
